UNITED STATES PATENT OFFICE.

LEWIS HOWES JOHNSON, OF BLOOMFIELD, NEW JERSEY, ASSIGNOR, BY MESNE ASSIGNMENTS, TO WESTERN ELECTRIC COMPANY, INCORPORATED, A CORPORATION OF NEW YORK.

TELEPHONE-EXCHANGE SYSTEM.

1,221,865.

Specification of Letters Patent. Patented Apr. 10, 1917.

Application filed June 7, 1915. Serial No. 32,683.

To all whom it may concern:

Be it known that I, LEWIS HOWES JOHNSON, a citizen of the United States, residing at Bloomfield, in the county of Essex and State of New Jersey, have invented certain new and useful Improvements in Telephone-Exchange Systems, of which the following is a full, clear, concise, and exact description.

10 This invention relates to telephone exchange systems and more particularly to such systems of the central energy type.

An object of this invention is to provide improved means for accurately ascertaining 15 the number of calls which an operator answers.

In accordance with this invention, there is provided at a central office a registering device common to an operator's position 20 which is operated when the answering end of a link circuit is connected with a calling telephone line. Means are also provided for disconnecting the registering device from the link circuit immediately upon the operation 25 thereof, in order that the registering device may thereafter be free for operation in connection with another link circuit. Means are also provided in association with each link circuit for causing the operation of the 30 registering device whenever a connected subscriber makes a recall.

For a more complete understanding of this invention, reference is made to the accompanying drawing showing one embodiment 35 thereof and wherein all apparatus is shown in its normal and unactuated condition.

In the drawing there is shown the usual subscribers' stations, A and B, terminating 40 at a central office at which is located a cord circuit C for interconnecting the stations. Subscriber A, wishing to converse with subscriber B, signals the operator in the usual manner. The operator, answering, inserts 45 the answering plug into a jack of the calling line, causing the operation of supervisory relay 1 included in bridge of the talking strands of the cord circuit. Relay 1, in operating, causes the operation of listening 50 relay 2 which connects the operator's telephone set across the talking strands of the cord circuit. The circuit for listening relay 2 may be traced from battery 3 through contact 4 of relay 5, lower winding of listen-

ing relay 2, contact 6 of relay 7, contact 8 55 of supervisory relay 1 and supervisory lamp 9 to ground. The operation of the listening relay 2 causes the operation of relay 15 associated with an electromagnetic registering device 16. The circuit of relay 15 may 60 be traced from battery 17, through both windings of relay 15, contact 18 of listening relay 2, contact 19 of relay 5, contact 20 and right-hand winding of relay 21, contact 22 65 of relay 7, sleeve contacts of the answering plug and jack, and the winding of cutoff relay 23 to ground. The actuation of relay 15 causes the electromagnetic registering device 16 to register the call which the operator has answered. The registering device, 70 in operating, short-circuits one winding of relay 15, thereupon permitting sufficient current to traverse the winding of relay 21 to actuate it. Relay 21, in operating, opens the hereinbefore traced circuit for relay 15 75 and completes a locking circuit for itself which may be traced from battery 24 through contact 25 and left-hand winding of relay 21, contact 22 of relay 7, sleeve contacts of the answering plug and jack, and the winding of cutoff relay 23 to ground. It is to be noted here that the electromagnetic registering device 16 and its associated relay 15 are common to an operator's position, and therefore, when the circuit of 80 relay 15 is opened at contact 20 of relay 21, the registering device is disconnected from cord circuit C, and is thereafter free to be associated with and operated by another cord circuit when it is used in answering a 85 call.

The operator finding that subscriber A desires to be connected to subscriber B, inserts the calling plug of the cord circuit into the jack of B's line, thereupon operating 95 relay 5 and cutoff relay 33. Relay 5, in operating, releases the listening relay 2, lights the calling supervisory lamp 26 and operates relay 27. The operation of relay 27 connects a source of ringing current 28 100 to B's line to operate the signal receiving device at station B. Relays 29 and 30 co-operate, in a manner well understood, with relay 27 in controlling the disconnection of the source of ringing current 28 from B's 105 line upon the removal of the receiver from the switchhook at station B. When the ringing current has been removed from the

called line, calling supervisory relay 35 operates to efface the calling supervisory lamp 26.

At the conclusion of the conversation, 5 subscribers A and B restore their receivers to the switchhooks, whereupon supervisory lamps 9 and 26 light to furnish disconnect signals. When A's receiver is restored to the switchhook, supervisory relay 1, controlling supervisory signal 9, releases, causing the operation of relay 7 over a circuit which may be traced from battery 3, through contact 36 of relay 5, contact 37 of key 38, contact 39 of relay 1, and the right-hand winding of relay 7 to ground. Relay 7, in operating, completes a locking circuit for itself which may be traced from battery 3 through contact 36 of relay 5, contact 40 of key 38, contact 41 and left-hand winding 15 of relay 7 to ground. In operating, relay 7 opens contact 22 thereof permitting relay 21 to release, and it also closes contact 42 in the circuit of a source of current 43 and interrupter 44. Should subscriber A thereafter, before the cord circuit C is disconnected from the jacks of lines A and B, desire to make another call, the removal of the receiver from the switchhook will cause the actuation of relay 1, whereupon supervisory lamp 9 will flash intermittently to furnish a recall signal to the operator. The operator, observing the flashing supervisory lamp, operates key 38 which actuates listening relay 2 to connect the operator's telephone set across the talking strands of the cord circuit. The operation of key 38 also releases relay 7 which retires the recall signal and closes contacts 6 and 22 of relay 7. The circuit of listening relay 2 may be 35 traced from battery 3 through contact 36 of relay 5, upper winding of listening relay 2, contact 45 of relay 35 and calling supervisory lamp 26 to ground. Ascertaining that subscriber A desires to be connected to 40 another telephone line terminating at the central office, the operator removes the calling plug from the jack of B's line and inserts it into the jack of the line wanted by subscriber A. When the calling plug is removed from the jack of B's line, relay 5 releases, opening the circuit for the upper winding of listening relay 2, but closing the hereinbefore traced circuit through the lower winding of this relay before breaking 45 the circuit through the upper winding. Relay 5, in releasing, also causes the operation of relay 15, whereupon the registering device 16 again counts, and in so doing, causes the operation of relay 21 which opens the 50 circuit of relay 15 and locks itself up over a path hereinbefore traced thereby disconnecting the registering device from the cord circuit. When the calling plug is inserted into the jack of the line wanted, the circuit through the lower winding of listening re-

lay 2 is interrupted, whereupon the operator's telephone set is disconnected from the talking strands of the cord circuit. Key 38 may be restored to normal position at any time after the operator communicates with subscriber A.

It will be readily apparent from the above description that this invention contemplates a registering device common to an operator's position, which is operated only when the answering plug is inserted into the jack of a calling line upon which there is a waiting subscriber. By the use of a system embodying this invention, it will be seen that an accurate record may be kept of the total number of calls which an operator answers, and that it is not possible to pad the registering device.

What is claimed is:

1. In a telephone exchange system, subscribers' lines terminating at a central office, a link circuit thereat for interconnecting said lines, an operator's telephone set, a relay controlled from a connected substation and actuated when the answering end of said link circuit is connected to a calling line to telephonically connect said operator's telephone set with the calling line, and a registering device at the central office for recording the number of calls answered by an operator, said registering device operating upon the actuation of said listening relay. 85
2. In a telephone exchange system, subscribers' lines terminating at a central office, a link circuit thereat for interconnecting said lines, an operator's telephone set, a relay controlled from a connected substation and actuated when the answering end of said link circuit is connected to a calling line to telephonically connect said operator's telephone set with the calling line, a registering device at the central office for recording the number of calls answered by an operator, said registering device operating upon the actuation of said listening relay, and relay mechanism actuated upon the operation of said registering device to disconnect said registering device from said link circuit. 90
3. In a telephone exchange system, calling and called subscribers' lines terminating at a central office, a link circuit thereat interconnecting said lines, recall signaling means associated with the answering end of said link circuit, means controlled by the restoration of the calling subscriber's receiver to and a subsequent removal thereof from the switchhook for causing the automatic operation of said recall signaling means to furnish a signal to the operator, a registering device at the central office, a relay controlled by said second named means for conditioning said registering device for operation, and electromagnetic mechanism controlled by the disconnection of the calling end of said link circuit from the called line for causing the 105 110 115 120 125 130

operation of said conditioned registering device, whereby said device registers the recall.

4. In a telephone exchange system, calling and called subscribers' lines terminating at a central office, a link circuit thereat interconnecting said lines, recall signaling means associated with the answering end of said link circuit, means controlled by the restoration of the calling subscriber's receiver to and a subsequent removal thereof from the switchhook for causing the automatic operation of said recall signaling means to furnish a signal to the operator, a registering device at the central office, a relay controlled

by said second named means for conditioning said registering device for operation, and electromagnetic mechanism controlled by the disconnection of the calling end of said link circuit from the called line for causing the 20 operation of said conditioned registering device, whereby said device registers the recall, the operation of said registering device causing the actuation of said relay to disconnect said registering device from said link 25 circuit.

In witness whereof, I hereunto subscribe my name this 3rd day of June A. D., 1915.

LEWIS HOWES JOHNSON.
